US00D894908S

(12) **United States Design Patent** (10) **Patent No.:** **US D894,908 S**
(45) **Date of Patent:** **** Sep. 1, 2020**

(54) **ELECTROMAGNETIC RADIATION
CONVERTER**

(71) Applicant: **American Aires Inc.**, Vaughan, Ontario (CA)

(72) Inventor: **Igor Nikolaevich Serov**, Saint-Petersburg (RU)

(73) Assignee: **American Aires Inc.**, Vaughan, Ontario (CA)

(**) Term: **15 Years**

(21) Appl. No.: **29/649,183**

(22) Filed: **May 28, 2018**

(51) **LOC (12) Cl.** **14-02**

(52) **U.S. Cl.**

USPC **D14/439; D14/240**

(58) **Field of Classification Search**

USPC D14/230-238, 217, 238.1, 240, 242, 248, D14/250, 253, 299, 343, 356, 358, 432, D14/433, 435-437, 439, 440; D13/103, D13/110, 133, 146, 158, 182, 184; D20/11; D19/9-12

(57) **CLAIM**

The ornamental design for an electromagnetic radiation converter, as shown and described.

DESCRIPTION

The file of this patent contains at least one drawing/photograph executed in color. Copies of this patent with color drawing(s)photograph(s) will be provided by the Office upon request and payment of the necessary fee.

FIG. 1 is a top perspective view of the electromagnetic radiation converter showing my new design;

FIG. 2 is a bottom perspective view thereof;

FIG. 3 is a top plan view thereof;

FIG. 4 is a bottom plan view thereof;

FIG. 5 is a first side view thereof, the opposite side being identical in appearance;

FIG. 6 is a second side view thereof, the opposite side being identical in appearance;

FIG. 7 is an enlarged view of a central medallion of FIG. 1; and,

FIG. 8 is an isolated view of a portion of the surface pattern of FIG. 1, taken from the corner.

1 Claim, 6 Drawing Sheets
(5 of 6 Drawing Sheet(s) Filed in Color)
